DRAWER SUSPENSION

Clarence W. Straubel, Youngstown, Ohio, assignor to The General Fireproofing Company, Youngstown, Ohio, a corporation of Ohio

Application September 30, 1942, Serial No. 460,309

2 Claims. (Cl. 45—77)

This invention relates to an improved mounting for the drawers of filing cabinets, and more particularly to a novel suspension for drawers of vertical filing cabinets.

One of the objects of the invention is to provide a novel suspension carriage which moves progressively slower than the drawer as the latter is pulled out of the cabinet thereby to fully and adequately support or sustain the weight of the drawer and its contents when the latter is moved completely out of the cabinet. In that connection, one of the features of the invention resides in providing a case channel, or its equivalent, and a novel sliding suspension including opposite suspension members each carrying a plurality of pairs of loose or free travelling rollers and a plurality of pairs of relatively fixed rollers mounted on non-fixed pinion bearings. It will thus be apparent that the suspension contains all of the rollers both travelling and relatively fixed while the case channel and drawer runner have no rollers but merely serve as guides for the suspension members.

Another object of the invention is to provide a drawer suspension whose structural features and characteristics lend themselves to embodiment in either metal, plastic, glass, wood or other material, composition or combination structures, thereby increasing the range of application of the invention to different types and forms of vertical file cabinets.

A further object is to provide a construction which lends itself to embodiment in a cradle type suspension, that is the type wherein the individual suspension members are connected by transverse ties or cross members.

With the above and other objects in view, which will more readily appear as the nature of the invention is better understood, the same consists in the novel construction, combination and arrangement of parts hereinafter more fully described and claimed.

A preferred and practical embodiment of the invention is shown in the accompanying drawings in which:

Fig. 1 is a perspective view illustrating the improved suspension as applied to metal cabinet construction.

Fig. 2 is a perspective view illustrating the improvements embodied in wood or other non-metallic cabinet construction.

Fig. 3 is a top plan view of one of the suspension members shown in Fig. 1 mounted in a cabinet.

Fig. 4 is a side elevation, partly in section, of the construction shown in Fig. 3.

Fig. 5 is an elevation of the front end of the construction shown in Fig. 4, illustrating a complete case channel, suspension member, and drawer runner in assembled operative relation.

Fig. 6 is a detail vertical section taken on the line 6—6 of Fig. 4.

Fig. 7 is a detail vertical section taken on the line 7—7 of Fig. 4.

Similar reference characters designate corresponding parts throughout the several figures of the drawings.

According to the embodiment of the invention shown in the drawings, the same includes in its organization, a vertical filing cabinet or "case" A intended to receive a plurality of sliding drawers B. At each drawer location the cabinet is provided interiorly with opposite case channels C. These channels receive the progressive suspension designated generally as D and which cooperates with runners E on opposite sides of the drawer to support the drawer in its sliding movements into and out of the cabinet. In connection with the case channels C, it will be understood that each may be formed as a unit and affixed to the inner side of the cabinet, or, on the other hand, the said inner side of the cabinet may be used as the base or bottom of the channel by affixing the upper and lower flange or track portions in proper spaced relation direct to the cabinet side wall as shown in Fig. 2. In other words, where the type of manufacturing procedure makes it desirable, the channels may be made up as preformed units, or alternatively the roller tracks may be secured directly to the cabinet walls before or after they are assembled in cabinet form.

Referring to the structural features of the case channel members C in Fig. 1, wherein metal construction is shown, it will be observed that each of the same includes a body or web 1 having the upper flange 2 and the lower flange 3, the front end being open while the rear end is substantially closed by the laterally offset stop or abutment member 4. In accordance with the usual practice, these stop members may be provided with felt or equivalent facings 4a for partially absorbing shock and deadening noise incident to the carriage abutting therewith at the end of its inward movement. The inwardly offset flanges 2 and 3 of the channel members may each be provided with marginal angularly disposed lip portions extending or projecting downwardly, that is in the same direction, with the result that the

lip 2a of the upper flange cooperates with the web 1 to provide a roller guiding channel while, in the example shown, the lip 3a of the lower flange serves as a reinforcement for sustaining the rolling load imposed on the upper surface of the flange 3.

The drawer runners E each preferably consists of a vertical body portion 5 with lower and upper flanges 6 and 7 offset in opposite directions. Each runner has its body 5 secured to the side wall of the drawer B and may have the lower flange 6 engaging the bottom of the drawer while the flange 7 projects outwardly and is adapted to be engaged by the peripheries of the rollers presently to be described in connection with the elements of the suspension D (Fig. 4).

The said suspension D includes in its organization, the opposite individual suspension members or arms d each having a substantially vertical wall 8 and the lower and upper inwardly offset flanges 9 and 10. The flanges 9 and 10 of each arm d are provided with the substantially right angularly disposed lip portions 9a and 10a respectively which extend upwardly and therefore in the same direction. The opposite suspension members d are connected by the transverse ties or straps 11 and 12 to unite the suspension members and thus form the carriage or suspension D. As will be apparent from Fig. 1, the tie or strap 11 is disposed in a horizontal plane at the front of the carriage while the tie or strap 12 is disposed vertically at the rear end of the carriage.

The suspension members d are each provided with the forward, intermediate, and rear drawer supporting travelling rollers 13, 14 and 15, which, as compared with sets of relatively fixed yet free rolling and vertically movable rollers 16-17, later described, are of smaller diameter. Each roller 13 of the forward pair is provided with retaining stud 13a operating in a slot 13b, or its equivalent, of a retainer plate 13c carried by the related arm d. At their bottoms these rollers engage the bottom flange 9 of the arm d. Each roller 14 is in turn limited in its travelling movement by a bottom slotted or equivalent guide 14a carried by the inner face of the side wall 8 of the related arm below the upper flange 10, and each roller 15 is limited in its travelling movement by a top slotted guide or cage 15a carried by the upper face of the flange 10. The rollers 14 and 15 are provided respectively with the axial studs or projections 14b and 15b and the guides 14a, 15a are formed with lips 14', 15', respectively, with which said projections cooperate to retain the rollers 14, 15 in their guides or cages so that they will not become accidentally displaced. The guides or retainers 14a and 15a are located respectively below and above the top flanges 10 of the arms d of the suspension D and both pairs of said rollers are disposed at higher elevations than the forward pair of rollers 13. The purpose of this arrangement is to enable the upper peripheries of the rollers 13 on one hand, and the bottom peripheries of the rollers 14 on the other hand, to engage the lower and upper faces respectively of the upper flange 7 of the runner E, and, moreover, to enable the upper peripheries of the rollers 15 of the rear pair to engage the bottom faces of the upper flanges 2 of the case channels.

The inner faces of the webs 8 of the suspension members also carry and house pairs of feeding rollers 16 and 17 which are of larger diameter than the rollers 13, 14, 15 and are relatively fixed in a horizontal direction in the sense that they do not travel although their studs 16a and 17a are mounted to move in vertical slots 16b in the

side wall 8 while their peripheries project through the slots 16c and 17c of the lower flange 8 of the suspension member thereby to slidably support the entire suspension in travelling engagement with the upper face of the lower flange 8 of the case channel C.

The bottom flanges 8 of the suspension members 8 are provided with stop or abutment members 18 which are adapted to engage with the horizontal cross members A' of the frame so as to limit the outward movement of the entire suspension D. Likewise, the front ends of the lips 10a of the upper flange 10 of the suspension members are provided with upwardly projecting stops or abutments 19 adapted to engage with a drawer carried abutment 20 which will prevent the drawer from being moved too far outwardly with respect to the suspension. Yet, by manually lifting the drawer at the front, the drawer is easily removable from the suspension.

The operation of the construction shown in Fig. 1 is as follows:

Assuming that the drawer B is closed, that is, fully in the cabinet, as shown in Fig. 4, it will be apparent that the lower peripheries of the rollers 16 and 17 which project through the slots 16c and 17c in the flange 8 are in rolling engagement with the upper roller bearing faces of the lower flanges 8 of the case channel C. Also, the flanges 7 of the drawer runners E are in engagement with the upper peripheries of the rollers 16 and 17. The forward travelling rollers 13 of each suspension member are located at the rear ends of their guides and their bottom peripheries have a tractive engagement with the upper faces of the lower flanges 8 of the suspension members d and also, have tractive supporting engagement at their upper peripheries with the bottom faces of the flanges 7 of the drawer runners. The intermediate travelling rollers 14 of each suspension member are normally at the rear ends of their guides and have their lower peripheries in tractive engagement with the upper faces of the flanges 7 of the drawer runners while their upper peripheries are in tractive engagement with the lower faces of the upper flanges 10 of the individual suspension members or arms. The rear pair of rollers 15 are at the forward ends of their guides and travel between the tops of said flanges 10 and the lower faces of the upper roller bearing flanges 2 of the case channels. As the drawer B is manually pulled outwardly of the cabinet A, the rollers 13 and 14 advance in their guides while rollers 15 retreat (Fig. 1) and the entire suspension D is propelled outwardly of the casing by the sets of rollers 16-17 at substantially half the speed of the movement of the drawer B on rollers 13, 14, and 15. When the drawer is fully pulled out of the cabinet, the suspension members d will rigidly support the drawer because substantially the rear half thereof is still within the limits of the case channels C and cannot fulcrum downwardly because the rear pair of rollers 15 between parts 2 and 10 prevent such action. The relative differential and progressive movement between the drawer B and the suspension D, is due to the different diameters of the pairs of travelling rollers 13, 14 and 15 and the pairs of rollers 16 and 17 which are relatively fixed horizontally. That is to say, the said rollers 16 and 17 being of larger diameter than the rollers 13, 14 and 15 and bearing on the lower flange 8 of the case channel C, cause the carriage or suspension D to move out of the casing relatively slower than the drawer B moves relative to the suspension members d, be-

cause the travelling rollers 13, 14 and 15 of relatively small diameter permit the drawer to move out faster than the carriage.

The adaptation of the invention above described to wood or plastic or glass or other suitable material or combinations of construction is shown in Fig. 2. In this embodiment, the cabinet A2 having the cross pieces A3 at the front thereof, is provided with the case channels C' which consist of the wood members 21 and 22 suitably spaced to provide a channel therebetween. The drawer B' is slidably mounted in the drawer cabinet or case by the suspension D' which in turn slidably supports the drawer runners E' each including the offset flange 1a. The individual suspension members d' are connected by the transverse members 11a and 12a and the inner faces of each of said members d' are provided with the forward, intermediate, and rear travelling rollers 13x, 14x and 15x. Also the inner faces of the suspension members d' are provided with the suspension feeding rollers 16x and 17x which are relatively fixed or held against travelling movement in said suspension members. The travelling rollers 13x, 14x and 15x are mounted in grooves or recesses in the suspension members d'. All of the rollers in Fig. 2 perform the same functions in the same manner, with reference to the upper and lower roller bearing members 21 and 22 of the case channel C' and the flanges 1a of the drawer runners, as their counterparts described in Fig. 1.

The upper members 21 of the case members C' (Fig. 2) are provided with stops 23 which engage with abutments 24 on the top of each of the suspension members d' of the carriage to thus limit the outward movement of the carriage relative to the cabinet A2. The bottom of the drawer B' carries the stops 25 which are adapted to engage with the inner edge of the transverse member 11a of the entire suspension D' to limit the outward movement of the drawer B' relative to the suspension. It will thus be apparent that the arrangement of stops and abutments in Fig. 2 is somewhat different from that in Fig. 1. In the latter figure, the outward movement of the carriage or suspension is stopped relative to the cabinet by the abutments 18 on the carriage engaging with the transverse members A' of the cabinet whereas in Fig. 2 the outward movement of the carriage relative to the cabinet is limited by the stops 23 on the case channels and the abutments 24 on the suspension members d' of the carriage. In Fig. 1 the outward limit of the drawer B is checked relative to the members 8 of the carriage D by the engagement of the stops 19 on the members d' engaging the abutments 20 carried by the drawer sides. In Fig. 2, however, the outward limit of the drawer B' is shown as checked by the stops 25 on the drawer bottom engaging with the transverse member 11a on the carriage.

The operation of the construction shown in Fig. 2 is as follows:

When the drawer B' is fully in the cabinet A2, the flanges 1a of the drawer runners E' have their underfaces resting on the rollers 13x, 16x and 17x. The upper faces of the flanges 1a are in tractive engagement with the rollers 14x. As the drawer is pulled outwardly the rollers 13x, 14x and 15x which are of smaller diameter than the rollers 16x and 17x permit of the drawer being pulled out of the cabinet approximately twice as fast as the rollers 16x and 17x will feed the carriage D' relative to the bottom member 22 of the case channel C'.

From the foregoing, it will be apparent that in both embodiments of the invention the distinguishing characteristic is the provision of a suspension which carries all of the rollers, namely, spaced pairs of large relatively fixed rollers having an engagement with the drawer runners and case channels, and a plurality of travelling rollers mounted in the carriage and slidably supporting the drawer relative to the carriage so that it may move faster out of the cabinet than the carriage. The advantage of the arrangement is that its desirable features may be incorporated either in steel or wood, metal, plastic, glass, compositions or combinations of suitable material while at the same time preserving all of the advantages of a strong and easily operated suspension. In that connection it will be apparent that with respect to the case channels C and C', both present upper and lower roller bearing faces for the rollers of the suspension. Also, while in the case of the metal embodiment, the rollers, 13, 14, 15, are held in guides, formed by metallic plates fashioned or bent to form cages in the wood, plastic, glass or other form of construction the same result is obtained by grooving or recessing the sides of the suspension members, and/or in using metal strips as retainers.

It may also be pointed out that all of the several pairs or sets of rollers, more or less, are free rolling in the sense that none of them have fixed axle pinions or studs. With the relatively long paths of travel, roller tread and track wear are reduced or, in other words, all wear is distributed over a greater surface area. Also, it may be pointed out that while the rollers 16 and 17 are relatively fixed in a horizontal direction, they are free to move vertically and hence have no fixed axle pinion. Their vertical movement, in addition to rolling, insures constant contact of rollers 13 and 14 with the drawer runners E.

Without further description, it is thought that the features and advantages of the invention will be readily apparent to those skilled in the art, and it will of course be understood that changes in the form, proportion and arrangement of parts may be resorted to without departing from the spirit of the invention and scope of the appended claims.

I claim:

50. 1. In a drawer suspension for filing cabinets and the like, a casing having a drawer-accommodating space, upper and lower forwardly and rearwardly extending track members carried by said casing at each side of the drawer-accommodating space therein, a drawer, a runner carried by said drawer at each side thereof and extending longitudinally relatively thereto, a pair of elongated suspension members free with respect to said track members and said runners and disposed at opposite sides of the drawer, respectively, and between the related upper and lower track members, respectively, each suspension member including an upper and a lower track element, a forward roller, a rear roller and an intermediate roller carried by each suspension member, means retaining said front and rear rollers in assembly with said suspension members for free traveling movement longitudinally with respect thereto, each forward roller being interposed between and being rollable upon the lower track element of the related suspension member and the related drawer runner, each rear roller being interposed between and being rollable upon the related upper track member of the casing and the upper track element of the related suspension member,
- 55.
- 60.
- 65.
- 70.
- 75.

each intermediate roller being interposed between and being rollable upon the upper track element of the related suspension member and the related drawer runner, and other rollers carried by each suspension member rearwardly of the forward roller carried thereby and immovable longitudinally with respect thereto and interposed between and rollable upon the related drawer runner and the related lower track member of the casing, each intermediate roller including a trunnion, and means connected to each suspension member and cooperating with the trunnion of the related intermediate roller to retain the latter assembled with the suspension member for free traveling movement longitudinally with respect thereto.

2. In a drawer suspension for filing cabinets and the like, a casing having a drawer-accommodating space, upper and lower forwardly and rearwardly extending track members carried by said casing at each side of the drawer-accommodating space therein, a drawer, a runner carried by said drawer at each side thereof and extending longitudinally relatively thereto, a pair of elongated suspension members free with respect to said track members and said runners and disposed at opposite sides of the drawer, respectively, and between the related upper and lower track members, respectively, each suspension

member including an upper and a lower track element, a forward roller, a rear roller and an intermediate roller carried by each suspension member, means retaining said front and rear rollers in assembly with said suspension members for free traveling movement, longitudinally with respect thereto, each forward roller being interposed between and being rollable upon the lower track element of the related suspension member and the related drawer runner, each rear roller being interposed between and being rollable upon the related upper track member of the casing and the upper track element of the related suspension member, each intermediate roller being interposed between and being rollable upon the upper track element of the related suspension member and the related drawer runner, and other rollers carried by each suspension member rearwardly of the forward roller carried thereby and immovable longitudinally with respect thereto and interposed between and rollable upon the related drawer runner and the related lower track member of the casing, and means connected to each suspension member and cooperating with the related intermediate roller to retain the latter permanently assembled with the suspension member for free longitudinal traveling movement relative thereto.

CLARENCE W. STRAUBEL
